UNITED STATES PATENT OFFICE.

LUTHER SCHAEFFER, OF CHICAGO, ILLINOIS, ASSIGNOR TO HENRY E. PETTY AND JOHN McFEELY, BOTH OF INDIANAPOLIS, INDIANA, AND MILTON E. PETTY, OF CHICAGO, ILLINOIS.

CENTRIFUGAL GOVERNOR-SWITCH.

1,122,548.

Specification of Letters Patent. Patented Dec. 29, 1914.

Application filed May 9, 1912. Serial No. 696,210.

To all whom it may concern:

Be it known that I, LUTHER SCHAEFFER, a citizen of the United States, residing at Chicago, in the county of Cook, State of Illinois, have invented certain new and useful Improvements in Centrifugal Governor-Switches; and I do hereby declare the following to be a full, clear, and exact description of the invention, such as will enable others skilled in the art to which it appertains to make and use the same.

This invention relates to certain novel and useful improvements in centrifugal governor switches, and has particular application to a device of the class described adapted especially for employment in connection with moving picture machines, although I wish it to be understood that the invention is not limited in its useful application to this particular purpose.

In carrying out my invention, it is my purpose to provide a simple, reliable and efficient centrifugal governor switch which may be readily applied in operative position, which is positive in its operation and which may be manufactured and marketed at a relatively low cost.

With the above recited objects and others of a similar nature in view, my invention consists in the construction, combination and arrangement of parts set forth in and falling within the scope of the appended claims.

In the accompanying drawings, like characters of reference indicate like parts throughout and Figure 1 is an end view of a device embodying my invention. Fig. 2 is a longitudinal sectional view taken therethrough, the governor being shown as applied to a rotating shaft.

The centrifugal governor switch embodying my invention will be found particularly adapted for use in connection with a moving picture machine apparatus such as is shown and described in the patent to John McFeely, dated January 20, 1914, and numbered 1,084,651.

Referring now to the accompanying drawings in detail, the numeral 5 indicates a rotatable shaft upon which is mounted my improved switch which I will now proceed to describe in detail. This switch itself comprises a pair of metallic disks 8-8', the disk 8 having a central opening 9 therein. The central portion of the disk 8' carries a block or bushing 9' of insulating material

into which the end of the shaft 5 extends so that while the governor switch is securely fastened in the shaft 5, the grounding of the electric circuit is avoided. The disks are suitably spaced apart and are connected together at intervals by the transversely extending sleeves 10 through which sleeves pass the shanks of the screw pins 11. Each sleeve pivotally or swingingly supports a contact member 12, which is in the nature of a short cylindrical metallic block, each block being bored longitudinally and eccentrically as at 13 for the passage of its supporting sleeve. The sleeve is preferably made a little longer than its contact member so that the latter will not bind at its end against the adjacent faces of the disks but will swing loosely and freely.

The numeral 14 designates a metallic core which is inserted in the opening or aperture of the outside disk 8, said aperture being sufficiently large to avoid contact with the core and consequently any electrical connection. The core is fastened to a plate of insulating material 15, said plate carrying a contact strip 16 through which pass the binding screws 17 which connect the strip and the core. The numeral 18 designates an electrical connection secured to the strip 16 by the binding screw or post 19, said connection forming a terminal for the conducting wire 20. On the same side of the plate as the core, is a contact arm 21 adapted to bear against the adjacent face of the disk, said arm being connected by binding screws 22 and 23 with the metallic contact 24 which forms a terminal for the end of the conducting wire 25.

From the description thus far given it will be seen that as the shaft rotates, the governor switch will turn with the shaft so that the swinging contact blocks 12 will move by centrifugal force outward away from the core 14. Upon the stoppage of the shaft, the uppermost contact block 12 will drop down into contact with the core. As the spring contact arm 21 bears against the disk 8 at the outside of the governor switch, the current flowing through the conductor 25 will naturally pass through said arm and disk to the blocks 12 and thence to the core 14 and through the same to the contact 18 and conductor 20, when the governor switch is at rest.

While I have herein shown and described

one particular embodiment of my invention, I wish it to be understood that I do not confine myself to all the precise details of construction herein set forth by way of illustration, as modification and variation may be made without departing from the spirit of the invention or exceeding the scope of the appended claims.

What I claim is:

10. 1. The combination with a shaft, of a plurality of spaced members rotating with the shaft, a core arranged within the space between said members and out of electrical contact with such members, swinging contacts mounted upon the spaced members and adapted to swing by centrifugal action out of contact with the core and by gravity into contact with the same, the core forming one terminal of an electric circuit, and the other terminal of said circuit in electrical contact with one of the spaced members.
20. 2. The combination with a shaft, of a circuit closer comprising a plurality of substantially parallel spaced members rotating with the shaft, a core arranged in substantial alinement with the shaft within the space between the spaced members and out of electrical contact with such members, swinging contacts mounted upon the spaced members and adapted to swing by centrifugal action out of contact with the core and by gravity into contact with the same, the core forming one terminal of an electric circuit, and the other terminal for said circuit in electrical contact with one of the spaced members.
30. 3. The combination with a shaft, of a member rotating with the shaft, a core extending through the member but out of electrical contact therewith, a plurality of swinging contacts eccentrically mounted on the rotating member and adapted to swing by centrifugal action out of contact with the core and by gravity into contact with the same, a terminal for an electric circuit in electrical connection with the core, and a second terminal for said circuit in electrical contact with the rotating member.
40. 4. The combination with a shaft, of a circuit closer rotating with the shaft and comprising two spaced disk members, con-

tact members pivotally supported between the disk members, a core extending between the disk members and held out of electrical contact with such disk members, a contact member connected to the core and to one of the wires of an electric circuit, and a contact member bearing against one of the disks and connected with a second wire of the electric circuit.

5. The combination with a shaft, of a disk connected with the shaft but insulated therefrom, a second disk arranged substantially parallel therewith, but spaced apart from the first mentioned disk, said second disk having a central opening therein, a core projecting through said central opening into the space between the two disks, said core being held out of electrical contact with the disks, a plurality of swinging contacts supported by the disks and located between the latter, said contacts being adapted to swing by centrifugal action out of contact with the core and by gravity into contact with such core, a contact member connected to the core and to one of the wires of an electric circuit, and a contact member bearing against the second disk and connected to a second wire of the circuit.

6. The combination with a rotating shaft, of a circuit closer carried by the shaft and comprising a conducting body, a plurality of swinging contact members supported by the conducting body and adapted to swing outward when the shaft is turned, a conducting element against which certain of the swinging contacts will bear when the shaft is at rest, said conducting element being held out of electrical contact with the conducting body a contact arm bearing against the conducting body and connected to one of the wires of an electric circuit, and a contact connected with another wire of the electric circuit and electrically connected to the conducting element aforesaid.

In testimony whereof, I affix my signature, in presence of two witnesses.

LUTHER SCHAEFFER.
